UNITED STATES PATENT OFFICE.

BENNO VOM EIGEN, OF NEWARK, NEW JERSEY.

POCKET-BOOK FRAME.

SPECIFICATION forming part of Letters Patent No. 380,834, dated April 10, 1883.

Application filed December 30, 1887. Serial No. 259,374. (No model.)

To all whom it may concern:

Be it known that I, BENNO VOM EIGEN, of Newark, county of Essex, and State of New Jersey, have invented certain new and useful 5 Improvements in Pocket-Book Frames, of which the following is a specification.

This invention relates to certain improvements in pocket-book frames and means for fastening the same, whereby the reliable clamping of the leather and lining of the body of the pocket-book is obtained and the detaching of any part of the same from the frame prevented; and the invention consists of a pocket-book frame the jaws of which are bent in such 15 a manner that the side walls form with the upper inclined part an outer obtuse and an inner oblique angle, the outer obtuse angle reinforcing the jaws and producing the tight clamping of the same to the leather or other 20 fabric from which the body of the pocket-book is made.

The invention consists, secondly, of an improved locking device which is composed of an exterior casing attached to one jaw of the 25 frame and provided with end lugs for retaining an interior spring which is made integral with a laterally-extending tongue having a finger-piece, said tongue being guided in a recess of the casing and adapted to engage by a 30 slot a catch or projection on the second jaw, as will appear more fully hereinafter, and finally be pointed out in the claims.

In the accompanying drawings, Figure 1 represents a side elevation of my improved 35 pocket-book frame. Fig. 2 is a vertical transverse section, drawn on a larger scale, of one jaw of my improved frame, showing it applied to the fabric of which the body of the pocket-book is composed. Fig. 3 is a vertical trans- 40 verse section of the jaws and fastener on line xx , Fig. 1. Fig. 4 is a vertical longitudinal section of the fastening device of the frame, drawn on a larger scale; and Fig. 5 is a horizontal section of the fastener on line yy , Fig. 4.

Similar letters of reference indicate corresponding parts.

In the drawings, $A A'$ represent the jaws of which my improved pocket-book frame is made. The jaws are pivoted in the usual manner 50 at the ends and bent in such a manner that the outer and inner side walls, $a a'$, form with the upper inclined part, b , of the jaws, respect-

ively, an outer obtuse angle at d and an inner oblique angle at d' , as shown clearly in Fig. 3. The obtuse angle formed by the upper part 55 and the outer side wall of the jaws $A A'$ serves to re-enforce the same by imparting thereto a greater degree of stiffness than that possessed by the jaws heretofore in use.

My improved construction furnishes a sufficient space for the proper expansion of the edge of the fabric at the interior of the jaw, so that, and consequently, the fabric is not liable to be crowded out of the jaw when the edges of the jaw are closed on the same. Jaws of 60 65 the shape described have the further advantage that the lower edges of the same bind more tightly onto the fabric, so as to retain the same in a more perfect and reliable manner than is the case in the frames heretofore in use. 70

The jaws are locked together by a fastening device which consists of a casing, B , applied to the jaw A , and of a locking-spring, C , that engages a catch or projection, f^2 , on the jaw A' . The casing B is provided at its inner face 75 with a recess, e . The spring C is placed longitudinally in the casing B and made integral with a laterally-extending tongue, f , that passes through the recess e of the casing B , and that is provided at its outer end with a 80 finger-piece, D , which is riveted or otherwise attached to the tongue f . The ends of the spring C are retained by means of inwardly-bent lugs g , arranged at the ends of the casing 85 B , so that the same is held in position therein when the casing is attached to the jaw A , and cannot be removed therefrom. A slot, f' , in the tongue f serves to engage the projection f^2 on the jaw A' , so as to lock thereby the jaws together. The casing is attached to the jaw 90 A by means of projecting lugs g' at its end, which pass through recesses of the jaw A , and are bent over at the inside of the same, so as to form a rigid connection between the casing and jaw. By making the spring and tongue 95 in one piece and retaining the spring by the end lugs of the casing a very simple and effective fastener for pocket-book frames is obtained.

Having thus described my invention, I claim 100 as new and desire to secure by Letters Patent—

1. A pocket-book frame provided with jaws, the side walls of which are bent so as to form an obtuse outer and an oblique inner angle

with the top portion of the jaw, substantially as set forth.

2. The combination, in a pocket-book frame, with the jaws of the same, of an open-bottomed casing attached to one jaw and provided with a recess at the side, a spring located in said casing, said spring having a laterally-extending slotted tongue, and a projection or catch in the other jaw adapted to be engaged by said spring-tongue, substantially as set forth.

3. The combination, in a pocket-book frame, of one jaw provided with a casing open at the bottom, said casing having inwardly-bent lugs and a recess at the inner side, of a spring

retained in said casing, said spring having a laterally-extending tongue provided with a slot and finger-piece, and a projection or catch on the other jaw adapted to be engaged by the slot of the spring-tongue, substantially as set forth.

20

In testimony that I claim the foregoing as my invention I have signed my name in presence of two subscribing witnesses.

BENNO VOM EIGEN.
